UNITED STATES PATENT OFFICE.

FERDINAND A. PFEIFER, OF SPRINGFIELD, OHIO.

MECHANICAL HORN.

1,239,036.

Specification of Letters Patent. Patented Sept. 4, 1917.

Application filed October 29, 1912. Serial No. 728,335.

To all whom it may concern:

Be it known that I, FERDINAND A. PFEIFER, a citizen of the United States, residing at Springfield, in the county of Clark and State 5 of Ohio, have invented certain new and useful Improvements in Mechanical Horns, of which the following is a specification.

My invention relates to acoustic signals and particularly to mechanically operated 10 devices for producing sonorous tones.

The invention comprises a mechanically operated horn especially adapted for use as a warning signal upon automobiles, but is equally applicable to boats or other vessels 15 or traction cars. In an enlarged form the device is suitable for use as a fog horn in the coast safety service, while in a reduced or miniature form the device may be used in lieu of the usual bell or buzzer for call 20 signal purposes.

The object of the invention is to simplify the structure as well as the means and mode of operation of such devices whereby they will not only be cheapened in construction 25 but will be more efficient in use, compact and durable, capable of producing resonant tones of great volume and unlikely to get out of repair.

A further object of the invention is to 30 provide improved means for vibrating the diaphragm to produce the resonant tone by means of a succession of blows delivered to the diaphragm with great rapidity by a rapidly revolving vibrator.

With the above primary and other incidental objects in view as will more fully appear in the specification, the invention 35 consists of the features of construction, the parts and combinations thereof and the mode 40 of operation, or their equivalents, as hereininafter described and set forth in the claims.

Referring to the drawings, Figure 1 is a side elevation partly in section of a manually operated signal apparatus forming the subject matter hereof. Fig. 2 is a perspective view of the rotor or vibrator and its spiral actuating bar. Fig. 3 is a plan view of the rotor showing its relation to the diaphragm. Fig. 4 is a detail sectional view of the rotor or vibrator. Fig. 5 is a side elevation partly in section of an assembled apparatus of modified form, embodying a spring for the return of the spiral actuating bar. Figs. 6 and 7 are detail views of the interengaging 50 connection between the actuating bar and the retracting spring. Fig. 8 is a detail plan

view of a modification whereby a greater number of blows may be delivered to the diaphragm thereby increasing its vibration. Fig. 9 illustrates a modification of the manually operated apparatus. Fig. 10 is an interior view of the housing shown in Fig. 9.

Like parts are indicated by similar characters of reference throughout the several views.

In constructing the device there is employed a vibratory diaphragm 1 preferably of sheet metal located within a housing or chamber 2. The housing or chamber 2 is preferably formed of two separable side 70 members 3 and 4 between the margins of which the diaphragm 1 is clamped. The side members 3 and 4 are engaged one with the other with the edge of the diaphragm interposed therebetween by means of screws 75 5. The forward side member 4 is extended forward and outward to form a flaring resonance chamber or horn 6 by which the sound produced by the vibration of the diaphragm 1 is magnified and projected in the 80 desired direction. Projecting from the rear wall 3 of the circular housing or chamber 2 and in a plane perpendicular to said chamber and diaphragm is a semicircular extension 7 of the housing or chamber 2 within 85 which is located the rotary vibrator which upon movement engages and vibrates the diaphragm 1. The semicircular housing extension 7 is provided upon one side with a bearing sleeve 8 which projects within the 90 extension, while the opposite side of the housing extension is provided with a second sleeve 9 in axial alinement with the first mentioned sleeve. Adjustably secured by a set screw 10 within the sleeve 9 is a tubular casing 11. The inner end of the tubular casing 11 is preferably, though not necessarily, chamfered to form a reduced thrust bearing for the rotary vibrator which revolves in a plane intermediate the inner extremity of the tubular casing 11 and the inner end of the bearing sleeve 8. The adjacent extremities of the bearing sleeve 8 and tubular casing 11 form lateral or thrust 95 bearings for the rotor on opposite sides thereof. The rotary vibrator comprises a revoluble carrier or runner 12 which in the drawing has been shown in the form of a wheel having an annular rim, and radial spokes, but which may be a simple disk. Located in spaced relation about the periphery of the carrier or runner and pro-

jecting perpendicular to the plane thereof is a series of studs 13. Located upon each of the studs 13 is an annular contact member or perforated disk 14, the concentric opening of which is of much greater diameter than that of the stud whereby the contact members will be permitted free movement through a limited distance in any direction as well as a free rotary movement 10 about the stud 13. The contact members may be secured in position upon the stud 13 by any suitable head, nut or other fastening device, but for convenience of manufacture are preferably secured by a split 15 ring 15 of spring material which engages in suitable notches 16 provided in the inner sides of the studs 13. The relation of the several parts is clearly illustrated in the detail view Fig. 4. The carrier or runner 12 is provided with a central rectangular opening 17 the sides of which are slightly beveled as shown in Fig. 3. Extending through 20 the central opening 17 of the carrier or runner 12 and reciprocating within the bearing sleeve 8 and the tubular casing 11 is a spiral actuating bar 18. The actuating bar 18 is preferably formed from a flat strip of material by twisting the said strip into a helical formation as shown in Fig. 2. It is obvious, 25 however, that a round rod having a helical groove of comparatively great pitch cut therein may be substituted for the spiral actuating bar 18. The actuating bar 18 is preferably formed with a flat extension 19 at either extremity. A knob or handle 20 is provided upon the extremity of the bar 18 for the convenience of the operator in reciprocating the bar. Inasmuch as the carrier or runner is held against lateral displacement 30 between the adjacent ends of the bearing sleeve 8 and the tubular casing 11, the reciprocation of the actuating bar 18 within the bearing sleeve 8 and the tubular casing 11 and through the central opening 35 17 of the runner will cause the carrier or runner to rotate at a very high rate of speed. The centrifugal tendency due to the rapid rotation of the runner or carrier causes the contact members 14 to be thrown outward 40 against the stud 13 to the limit of their movement. The relation of the carrier or runner 12 with the diaphragm 1 is such that the contact members 14 when in their extended position will strike the diaphragm 45 as the carrier is rotated thereby producing a succession of sharp blows thereon. As each succeeding contact member 14 engages the diaphragm the contact member will yield against the centrifugal tendency to 50 permit it to clear the diaphragm after delivering its blow thereto. The engagement of the contact member with the diaphragm causes the former to rebound after which it may or may not strike the diaphragm a second time before passing out of its range of

action. The great range of free play of the contact members about the studs 13 and their rotary movement about such studs upon engaging the diaphragm obviates friction between the vibrator and the diaphragm. In Fig. 3 the contacting member 14 is shown as having yielded against the centrifugal tendency to permit it to clear the diaphragm with which it is shown in contact while the remaining contact members 55 14 are shown in their outermost positions to which they have been carried by centrifugal tendency ready to engage the diaphragm 1 as they are passed to their operating position by the rotation of the carrier. There will be little or no tendency for the rotary 60 vibrator to revolve the spiral actuating bar in unison with it. However, any such tendency as may occur will be resisted by the grasp of the operator's hand upon the operating knob or handle 20. As the spiral actuating bar 18 approaches the limit of its stroke in either direction the helical formation thereof passes entirely through the rotary vibrator which is then engaged upon the flattened extremities 19 of the actuating bar. As the rotary vibrator passes upon the flattened extremities of the actuating bar the reciprocation of the bar will no longer tend to rotate the vibrator which 65 by the engagement of the flat portion 19 within the rectangular opening 17 will be prevented from further independent rotation. However, by the impetus given it by the reciprocation of the spiral portion of the reciprocating actuating bar the vibrator will tend to rotate the said actuating bar in unison with it. This rotary movement of the actuating bar may be resisted by the grasp of the operator upon the handle or 70 knob 20 thereby arresting the rotary movement of the vibrator, although if the operator releases the grasp upon the handle or knob no harm can result and the energy necessary to rotate the actuating bar and the handle 2 carried thereby will absorb the momentum of the vibrator and gradually bring the latter to a state of rest. If the flat extremities 19 were not provided at the opposite ends of the actuating bar but the helical formation extended to the extreme ends 75 thereof the momentum of the rotary vibrator would tend to further reciprocate the actuating bar 18 after the latter had reached the limit of its stroke thereby subjecting the several parts to excessive strain and wear. However, such excessive strain and wear is entirely obviated by the employment of the flat extremities 19 upon the actuating bar. In Fig. 5 there is shown a modified apparatus in which the diaphragm 1 is located in a plane parallel with the axis of the horn 6 instead of perpendicular thereto as shown in Fig. 1. Likewise in this construction the actuating bar reciprocates in a line parallel 80

with the axis of the horn 6 instead of transversely thereto as within the previously described construction. The construction of the housing 2, the extension 7, bearing sleeve 8, tubular casing 11 and the rotary vibrator is exactly the same as that previously described except that their positions in relation to the horn have been changed. In this construction the extremity of the tubular casing 11 is preferably supported by a bracket 21 attached to the flaring portion of the horn 6. This construction is especially adapted for use where the apparatus is to be operated from a distant point by means of a cord 22 engaged with the actuating bar 18 by a swivel 23. The actuating bar 18 as shown in Fig. 5 is adapted to be reciprocated in one direction by a pull upon the cord 22 and thereafter returned to its normal position by a retracting spring 24. The spring 24 not only retracts the actuating bar 18 at each operation but it further resists any tendency of the actuating bar to rotate during its reciprocatory movement. To accomplish the latter purpose one end of the retracting spring 24 is attached to the tubular casing 11 or to the frame of the apparatus as shown at 25 while the opposite end of the spring 24 is attached to a clutch collar 26 loosely journaled upon the actuating bar 18 and capable of a longitudinal sliding movement thereon. The clutch collar 26 is provided with clutch teeth 27 projecting from the face thereof and adapted to engage similar clutch teeth 28 upon a second clutch collar 29 rigidly secured upon the extremity of the actuating bar 18. The length of the retracting spring 24 is such that when the actuating bar 18 is in its initial position or at the limit of its stroke in one direction the clutch collars 26 and 29 will be separated one from the other and the actuating bar together with the rotary vibrator and the clutch collar 29 carried by the actuating bar will be free to rotate independent of the retracting spring 24 and the clutch collar 26 with which the spring is engaged. However, the initial reciprocatory movement of the actuating bar 18 will draw the clutch collar 29 into engagement with the clutch collar 26 whereupon further reciprocatory movement of the actuating bar will cause the retracting spring 24 to be compressed. The helical trend of the spiral actuating bar and the helical retracting spring 24 are preferably in opposite directions whereby any tendency of the actuating bar to rotate during its reciprocatory movement will be against the torsional tension of the retracting spring 24 which will thereby resist such revoluble tendency. When the reciprocating actuating bar 18 has been moved to the limit of its stroke thereby placing the retracting spring 24 under tension the cord 22 is released, whereupon the retracting spring will reciprocate the actuating bar in the opposite direction causing the vibrator to be again violently rotated. As the reciprocating bar approaches the limit of its return stroke the clutch collars 26 and 29 are disengaged thereby permitting the actuating bar and vibrator to rotate freely until the momentum of the latter has been exhausted. During the final free rotary movement the swivel 23 prevents the cord 22 from being twisted. In Fig. 6 the clutch collars 26 and 29 have been shown interengaged one with the other as is the case during the reciprocatory movement of the actuating bar. In Fig. 7 the said clutch collars are shown in their separated position as would occur at the limit of the return stroke of the actuating bar. It is to be noted that in the construction illustrated in Fig. 1 the operation of the device depends entirely upon manual effort, while in the construction shown in Fig. 5 the actuating bar is reciprocated by a manual effort in one direction but is returned automatically under the influence of the retracting spring 24.

In Fig. 8 there is shown a construction designed to increase the rapidity of the vibrations of the diaphragm 1. This is accomplished by securing to the diaphragm angularly projecting wings 42 extending in tangential relation with the rotary vibrator whereby the contact members 14 will engage the angular wings 42 before and after engaging the diaphragm. The contact members are thus made to deliver three blows one to each of the angular wings and one to the diaphragm intermediate the wings instead of delivering one blow as in the constructions previously shown and described.

In Fig. 9 there is illustrated a further modification of the apparatus embodying the diaphragm, resonance chamber, reciprocatory actuating bar and rotary vibrator all constructed exactly as is employed in the construction illustrated in Fig. 1. However, in the present modification the relative positions of the several parts have been changed whereby the actuating bar 18 will reciprocate in axial alignment with the resonance chamber 6 rotating the vibrator in a plane parallel with the diaphragm 1. The rotary vibrator is inclosed in a rearward extension 42 projecting from the rear housing member 3 in which is provided a concentric bearing sleeve 43 corresponding to the sleeve 8 of the former construction. The actuating bar 18 reciprocates within the bearing sleeve 43 and in a second bearing 44 provided in a transverse bar 45 secured to the inner walls of the housing member 3. The rotary vibrator is carried upon the actuating bar in a position intermediate the adjacent ends of the bearing sleeve 43 and 44.

the bearing 44 where as before stated it will be rotated in a plane parallel with the diaphragm 1. The diaphragm is provided with a central opening to permit the passage 5 of the actuating bar 18. Secured to the diaphragm are angularly projecting wings or plates 46 the extremities of which project into the path of travel of the contact members 14 of the rotary vibrator. The 10 engagement of the contact members 14 with the plates 46 vibrates the diaphragm 1 to produce the desired sound. In the drawing but two of the angular wings or plates 46 have been shown. It is obvious however 15 that any convenient number of such plates may be employed.

From the above description it will be apparent that there is thus produced a device of the character described possessing 20 the particular features of advantage before enumerated as desirable but which obviously is susceptible of modification in its form, proportion, detail construction and arrangement of parts without departing 25 from the principle involved or sacrificing any of its advantages.

While in order to comply with the statute, the invention has been herein described in language more or less specific as to certain 30 structural features, it is to be understood that the invention is not limited to any specific details but that the means and mechanism herein shown and described comprise but one mode of putting the invention into effect and the invention is therefore claimed broadly in any of its possible forms or 35 modifications within the scope of the appended claims.

Having thus described my invention, I 40 claim:

1. In an acoustic signal apparatus, a resonance chamber, a vibratory diaphragm, a rotary vibrator, an anvil comprising a segment of polygonal formation, the successive 45 faces of which extend in tangential relation to the path of travel of the rotary vibrator and are adapted to be successively engaged by the vibrator in its rotary movement, said anvil being connected with the diaphragm, whereby blows delivered to the anvil will be transmitted to the diaphragm 50 to cause a vibration thereof, substantially as specified.

2. In an acoustic signal apparatus, a resonance chamber, a vibratory diaphragm, a revolute carrier, a plurality of studs located 55 upon the carrier, an annular contact member engaged over each of the studs the opening of which is of greater diameter 60 than the stud, whereby the contact member will be permitted free movement for a limited distance about the stud, each of the studs being recessed upon its side nearest the axis of the carrier and an expansible 65 annular retaining member common to all

the studs expanded into the recesses of several studs to retain the contact members, the construction and arrangement being such that as the carrier is rotated, the contact members will engage the diaphragm. 70

3. In an acoustic signal apparatus, a resonance chamber, a vibratory diaphragm, a rotary vibrator adapted by its rotation to vibrate the diaphragm, thrust bearings for said vibrator located on the opposite sides 75 thereof, said vibrator being provided with a central orifice, and a spiral actuating bar engaging in the central orifice of the vibrator and by its reciprocation therethrough adapted to rotate the vibrator, the vibrator 80 being locked with the actuating bar against relative rotation as the latter approaches the limit of its stroke, the construction being such that the vibrator will tend to rotate the actuating bar by the impetus given it by the 85 prior reciprocatory movement of the bar, substantially as specified.

4. In an acoustic signal apparatus, a resonance chamber, a rotary vibrator, a vibratory diaphragm arranged tangentially 90 in relation to the vibrator and adapted to be engaged thereby as the vibrator is rotated, and wings projecting angularly from the diaphragm in positions also tangential in relation to the rotary vibrator and adapted to 95 be engaged thereby before and after the engagement of the diaphragm by the vibrator, substantially as specified.

5. In an acoustic signal apparatus, a resonance chamber, a vibratory diaphragm, 100 a rotary vibrator, means to actuate the rotary vibrator, extensions angularly disposed in relation one with the other carried by the diaphragm and projecting tangentially across into the path of the vibrator and adapted to be engaged thereby upon the rotation of the vibrator, substantially as specified. 105

6. In an acoustic signal apparatus, a resonance chamber, a vibratory diaphragm, a rotary vibrator adapted by its rotations to vibrate the diaphragm, a reciprocating actuating bar for the rotary vibrator capable of rotation, said actuating bar being adapted to cause the vibrator to rotate independently 110 of the rotation of the bar by its reciprocatory movement, and means for interengaging the bar and vibrator to cause them to rotate in unison as the bar approaches the limit 115 of its stroke.

7. In an acoustic signal apparatus, a resonance chamber, a rotary vibratory therefor, an actuating bar capable of both reciprocatory and revolute movement adapted by its reciprocatory movement to rotate the vibrator and means for interengaging the 120 vibrator and bar as the latter approaches the limit of its stroke, whereby the vibrator will tend to rotate the bar in unison therewith. 125

8. In an acoustic signal apparatus, a resonance chamber, a vibratory diaphragm, 130

a rotary vibrator, a spiral actuating bar for the vibrator, the vibrator and bar being capable of relative movement in an axial direction, said bar being further capable of 5 revoluble movement and means by which the actuating bar will be temporarily held against rotation during the relative movement of the vibrator and bar in an axial direction.

10 9. In a sound producing device a casing, a horn attached thereto, a diaphragm, a fixed anvil on said diaphragm, said casing having an extension, a tube in alinement therewith, a spring in said extension, a reciprocable 15 actuating rod doubly grooved helically, and a toothed wheel revoluble in a plane at right angles to said diaphragm and coöperating with said anvil, said rod being reciprocable through said tube and said wheel and rotating the latter by a portion of such reciprocation and means whereby the rod and wheel will be interengaged one with the other and caused to rotate in unison as the 20 rod approaches the limit of its reciprocatory movement.

25

10. In a sound producing device, a sounder, a vibrator therefor, an actuating rod for the vibrator capable of both reciprocatory and rotary movement, a spring tending to resist any rotary tendency of the rod during 30 its reciprocatory movement, said spring and rod being disengaged as the rod approaches the limit of its reciprocatory movement whereby the rod is permitted to rotate.

11. A sounder, a rotary member, an actuating bar capable of both reciprocatory and revoluble movement adapted by its reciprocatory movement to rotate the said rotary vibrator, and means for interengaging the rotary member and the bar as the latter approaches the limit of its stroke whereby the 35 said rotary vibrator and bar will tend to rotate in unison.

In testimony whereof, I have hereunto set my hand this 15th day of October, 1912.

FERDINAND A. PFEIFER.
